UNITED STATES PATENT OFFICE

THOMAS LOMBARDI, OF PORTVUE, PENNSYLVANIA.

POLISHER FOR ROLLS.

No. 921,549.

Specification of Letters Patent.

Patented May 11, 1909.

Application filed January 4, 1909. Serial No. 470,591.

To all whom it may concern:

Be it known that I, THOMAS LOMBARDI, a citizen of the United States of America, residing at Portvue, in the county of Allegheny and State of Pennsylvania, have invented certain new and useful Improvements in Polishers for Rolls, of which the following is a specification, reference being had therein to the accompanying drawing.

10 This invention relates to a polisher for rolls, and the primary object of my invention is to provide a novel polisher for cleansing rolls used in tin plate mills and similar structures where it is necessary to maintain the 15 rolls in a clean and polished condition to prevent matter from accumulating upon the same, and to insure a high grade product.

Another object of my invention is to provide a simple and self-adjusting polisher for 20 rolls that will not interfere with the pass between two rolls, and can be easily renewed when worn.

With the above and other objects in view which will more readily appear as the invention is better understood, the same consists in the novel construction combination and arrangement of parts to be presently described and then claimed.

In the drawings, Figure 1 is a front elevation of a pair of rolls equipped with my polisher, Fig. 2 is a vertical sectional view of the same, Fig. 3 is an enlarged front elevation of a portion of one of the polishers, Fig. 4 is a horizontal sectional view of the same, and Fig. 5 is a cross sectional view of one of the polishers.

In the accompanying drawings, 1 designates housings for rolls 2 and 3, the roll 2 being arranged above the roll 3 and providing a longitudinal pass 4 for sheet metal. The confronting sides of the housings 1 are provided with oppositely disposed brackets 5 and 6, the brackets 5 being located in front of the rolls 2 and 3, and directly above the 45 pass 4 of said rolls, while the brackets 6 are located at the rear of the rolls, adjacent to the roll 3 and below the pass 4. The brackets 5 and 6 are L-shaped and the horizontal portions of said brackets are adapted to support 50 channel-shaped holders 7, said holders extending longitudinally of the rolls 2 and 3. Each holder is provided with a plurality of longitudinal openings 8, and in each holder is placed a longitudinal plate 9, having openings 10, adapted to register with the openings 8. Arranged in each holder against the

plate 9 are a plurality of polishing blocks 11, having beveled edges 12 for engaging the rolls 2 and 3. The polishing blocks can be of emery or a similar abrasive material. The 60 polishing blocks are made of a size so that they can be conveniently placed in the holder by passing the same through the openings 8 and 10 and in order that each block can be shifted in the holder, the blocks are provided 65 with eyebolts 13. By inserting a rod or suitable instrument in the openings 8 and 10, and in engagement with the eyebolts 13, the polishing blocks can be easily shifted.

Although the polishing blocks 11 are in 70 spaced relation to each other, it will be observed that the entire surface of the rolls may be readily polished by the blocks by shifting the latter longitudinally in their holders, one block being shifted into the path of another 75 and vice versa.

To normally maintain the polishing blocks 11 in engagement with the rolls, the holders 7 are provided with set screws 14, adapted to engage the plate 9 as best shown in Fig. 4. 80

For retaining the holders in such a position that the blocks 11 will engage the rolls, each of the blocks 5 and 6 are provided with set screws 15 and encircling said set screws between the vertical portions of the brackets 85 and the holders, are coil springs 16, the tension of said springs forcing the holders toward the rolls. The set screws 15 are employed to prevent the holders from receding, and as shown in the drawings, these set 90 screws are adjusted their full limit.

Having now described my invention, what I claim as new, is;—

1. In a polisher for rolls, the combination with a support for the rolls to be polished, 95 oppositely disposed brackets carried by the support and arranged in operative relation with respect to the rolls to be polished, channel shaped holders movably mounted upon said brackets, said holders having longitudinal openings formed therein, a plate adjustably mounted in each holder and having openings registerable with the openings of said holder, polishing blocks movably mounted in engagement with the periphery 100 of said rolls by said plate of each holder, and means in connection with each bracket for moving said holders toward said rolls to hold the polishing blocks in engagement with the periphery thereof, substantially as described. 105
2. In a polisher for rolls, the combination

with a support for the rolls to be polished, oppositely disposed brackets carried by the support and arranged in operative relation with respect to the rolls to be polished, chan-
nel-shaped holders movably mounted upon
5 said brackets, said holders having longitudi-
nal openings formed therein, a plate adjust-
ably mounted in each holder and having
openings registerable with the openings of
10 said holder, and polishing blocks movably

arranged in each holder and adapted to be held in engagement with the periphery of said rolls by said plate of each holder.

In testimony whereof I affix my signature in the presence of two witnesses.

THOMAS LOMBARDI.
